UNITED STATES PATENT OFFICE.

ELIZABETH LEE, OF LITTLE FALLS, NEW YORK.

COMBINED WAIST AND SKIRT.

SPECIFICATION forming part of Letters Patent No. 444,001, dated January 6, 1891.

Application filed May 7, 1890. Serial No. 350,938. (No model.)

To all whom it may concern:

Be it known that I, ELIZABETH LEE, a citizen of the United States, residing at Little Falls, in the county of Herkimer and State of New York, have invented certain new and useful Improvements in Health-Garments, of which the following is a specification.

My invention relates to that class of garments for women's wear which are known as "combination garments," and are designed to remove the weight of the skirts from the hips and waist and to transfer it to the shoulders. So far as known to me, garments of this class hitherto not only have failed to accomplish fully all the hygienic results aimed at, particularly the most essential result—namely, to relieve the abdomen of all pressure—but they have also failed to be adopted extensively because it was impossible for women while using them to dress in a thoroughly neat and tasteful manner. Those who have a tendency to embonpoint have been obliged to discard them on account of the uncomfortable and altogether undesirable multiplication of thicknesses of fabric about the waist, and all have found them unbecoming on account of the ungraceful draping or lack of draping given to the outer or dress skirts and uncomfortable because of their tendency to cling to the limbs and interfere with the person in walking. My invention is intended to obviate all these difficulties, to increase the comfort-giving qualities of such garments, to remove all weight and pressure from the abdomen, to permit all parts of the body of the wearer to be clad with uniform thickness of fabric and warmth, to provide a garment which can be taken apart readily for the laundering of one part or the other, or for the replacing of one part by a new one, (as the bodice portion will become soiled much sooner and wear out much quicker than the skirt portion,) or for change of the material of one part or the other, according to the temperature or the occupation of the wearer, and to provide a garment which shall be acceptable to those who desire to exercise freely by reason of its non-interference with the person and to those who desire to dress fashionably by reason of its peculiar adaptability for fitting over in dress-making, and particu-

larly by reason of the easy and graceful flow which it imparts to the skirts and the avoidance of unnecessary and unsightly accumulation of material about the waist and upper portion of the hips.

To these ends my invention consists in the improved garment hereinafter described and claimed.

In the accompanying drawings, forming a part hereof, Figure 1 is a front view of one form of my improved garment as it would appear in use, the upper portion only of the skirt part being shown, and the dress-skirt being indicated in section. Fig. 2 is a side view of the same partly broken out. Fig. 3 is a rear view of the same, the upper portion of the bodice part being broken away. Fig. 4 is a diagrammatic view showing the relation of the dress-skirt, my improved garment, and the petticoat to one another and to the body of the wearer. Fig. 5 is a detail sectional view showing more clearly the construction of the garment and the mode of attaching the other skirts thereto. Fig. 6 is a similar view of another form to be described hereinafter.

The bodice portion 1 of the improved garment is made to fit snugly to the form and to extend below the waist-line 2 to about the upper line of the hips—that is, about the line of greatest fullness. It may have, as when it is to be worn by growing girls or by persons of unsymmetrical form, elastic shirred gores or gussets 3 at the sides, the same being formed by inserting elastic bands 4 into the material of the gusset and securing their ends to the adjacent portions of the bodice. A very light dress-waist may thus be worn directly over the bodice without the use of an intervening cover, which would be necessary in order to prevent the showing through of elastic laces and other devices of that sort which have been employed hitherto. The skirt portion 5 of the garment is fulled and gathered at the top, as shown at 6, and is secured to a supporting-band 7, preferably a bias band, which is then secured to the lower edge of the bodice portion 1. The fulling and gathering of the top of the skirt is essential in order to give that flow of the skirt itself, of the under skirt, and of the dress-skirt

away from the body which is necessary to impart a graceful outline and fall to the dress-skirt and to prevent that clinging of the skirts to the person which not only would be unsightly, but would interfere with free movement. It will be seen that this very desirable result could not be secured were both bodice and skirt cut in one piece, and that at the same time the securing of this 5 fulled and gathered top of the skirt to the bodice at the described distance below the waist-line makes it possible to secure this result without that bulky, uncomfortable, and unsightly plicating of material about 10 the waist which would be necessary were the garment cut in one piece and loose like an under-vest or other such garment. For this same reason, and, further, to prevent compression of and weight upon the abdomen, 15 fastening devices 8, such as buttons, are secured to the inside of the bias band 7—that is, to the side next the wearer, to which is secured the top of the petticoat 9. The petticoat is thus supported entirely by the bodice 20 and does not add another and unnecessary thickness about the waist and above the hips, the only covering over the hips between the waist and the dress-skirt being the lower portion of the bodice, which is worn as an ordinary corset-cover. 25

To the bodice and slightly below the waist-line are secured the devices 10 for supporting the dress-skirt 11. I prefer to employ eyes, as shown, to co-operate with hooks 12 30 on the dress-skirt. It will be observed that these supporting devices are all to the rear of the side lines of the bodice. This arrangement provides for holding the dress-skirt snugly and tightly to the body at the rear, 35 where weight and compression can do no harm, while in front and over the abdomen the dress-skirt is given a looseness and fullness, as clearly shown in Figs. 1, 2, and 4, thereby altogether avoiding weight and pressure where it would be injurious. Were no 40 means provided to prevent, the dress-skirt would sometimes, especially when the wearer is sitting, ride up on account of this very looseness and so become disarranged. Accordingly I have secured to the bodice in 45 front, at about one and one-half inch below the waist-line, or where the top of the dress-skirt rests naturally when the wearer is standing, an inverted hook 13, under which the top 50 of the dress-skirt is secured and so held in place, and at the same time without causing any pressure on the abdomen. 55

In the form presented in Fig. 6, which is especially adapted for use when the garment 60 is made up in "white" goods—that is, in cotton or linen—the supporting-band, instead of having the skirt portion 5 sewed thereto, and being itself sewed to the bodice portion at both edges, as represented in Fig. 5, is sewed 65 to the bodice portion at its upper edge only and has secured to its outer side buttons 14,

and the skirt portion 5', being fulled and gathered as before, is secured to said buttons instead of being sewed to the band. This arrangement is particularly desirable, as it 70 facilitates the separation of the garment for purposes of laundering, &c. The buttons 14 are preferably placed in alternation with the buttons 8 and may be covered with a flap, as shown. 75

The skirt portion 5 may be provided with draw-strings, if desired, as indicated in dotted line in Fig. 3.

Having thus described my invention, I claim— 80

1. The combination of a bodice adapted to fit snugly to the form, a supporting-band secured thereon at a distance below the waist-line about equal to the distance from the natural waist-line to the upper line of the 85 hips, fastening devices secured to said band to support a petticoat, and a skirt gathered and fulled at the top and also secured to said band, substantially as described.

2. The combination of a bodice adapted to fit snugly to the form, a supporting-band secured thereon at a distance below the waist-line about equal to the distance from the natural waist-line to the upper line of the hips, fastening devices secured to said band 95 to support a petticoat; a skirt fulled and gathered at the top and also secured to said band, and supporting devices for other skirts attached to the outside of the bodice at a little below the waist-line, substantially as de- 100 scribed.

3. The combination of a bodice adapted to fit snugly to the form, a supporting-band secured thereon at a distance below the waist-line about equal to the distance from the natural waist-line to the upper line of the hips, fastening devices secured to said band to support a petticoat, a skirt fulled and gathered at the top and also secured to said band, supporting devices for other skirts, attached 105 to the outside of the bodice at a little below the waist-line, and an inverted hook secured to the front of the bodice to engage with the outer skirt and prevent the same from riding up, substantially as described. 115

4. The combination of a bodice adapted to fit snugly to the form, a supporting-band sewed at its upper edge only to the inside of the bodice at a distance below the waist-line about equal to the distance from the natural 120 waist-line to the upper line of the hips, fastening devices secured to the inner side of said band to support a petticoat, fastening devices secured to the outside of said band, and a skirt gathered and fulled at the top 125 and adapted to be supported by said last-named fastening devices, substantially as described.
